UNITED STATES PATENT OFFICE.

REUBEN SLOTE, OF MOUNT VERNON, NEW YORK, ASSIGNOR TO SLOTE & SCHAFER, OF NEW YORK, N. Y., A COPARTNERSHIP CONSISTING OF REUBEN SLOTE AND JACOB I. SCHAFER.

DESIGN FOR A BUCKLE FOR LADIES' BELTS.

Application filed August 24, 1923. Serial No. 7,073. Term of patent 3½ years.

To all whom it may concern:

Be it known that I, REUBEN SLOTE, a citizen of the United States, residing at Mount Vernon, in the county of Westchester and State of New York, have invented a new, original, and ornamental Design for a Buckle for Ladies' Belts, of which the following is a specification, reference being had to the accompanying drawing, forming part thereof.

The figure is a plan view of a buckle for ladies' belts showing my new design.

I claim:

The ornamental design for a buckle for ladies' belts as shown.

REUBEN SLOTE.
